UNITED STATES PATENT OFFICE.

MIKE SUSTARSIC AND LOUIS FLORJANCIC, OF CLEVELAND, OHIO.

SLIDING AND SWINGING WINDOW SASHES.

Application filed January 30, 1922. Serial No. 532,681.

To all whom it may concern:

Be it known that we, MIKE SUSTARSIC and LOUIS FLORJANCIC, citizens of the United States, and residents of Cleveland, in the county of Cuyahoga and State of Ohio, have invented certain new and useful Improvements in Sliding and Swinging Window Sashes, of which we hereby declare the following to be a full, clear, and exact description, such as will enable others skilled in the art to which it appertains to make and use the same.

The objects of the invention are to provide improved forms of construction for window sashes permitting the sashes to assume a number of positions, including a substantially burglar proof position for ordinary use a ventilating position and a tilted or horizontal position enabling the window panes to be cleaned on both sides without stepping off from the floor.

In this construction the sashes are supported in adjustable positions by means of sash weights and cords which are not directly attached to the sashes but are attached to the inner extremities of link members which are guided in vertical grooves in the window frame and have thin lower extremities pivoted to the edges of the window sashes thus permitting the upper edges of the sashes to swing inwardly to a horizontal position where they are accessible for cleaning.

Also the sashes are provided with pivotal pins adjacent to their lower ends which move in the aforesaid vertical grooves and upon these pins the sashes swing freely in the frame.

The invention includes the employment of parallel vertical grooves and inclined and transverse grooves connecting the same at different levels thus permitting the sashes to be placed in several positions as follows:

First, permitting both the upper and lower sashes to be positioned between the outer grooves in the same vertical plane thus making it impossible for a burglar to raise or lower either of them.

Second, permitting the lower sash to be transferred to positions between the upper parts of the inner grooves and the outer

sash to be lowered along the outer grooves and tilted forward underneath the lower sash to make it accessible for cleaning.

In use the lower sash must first be tilted forward on its pivots and this action permits the raising of the lower sash and the lowering of the upper sash.

The invention includes weather excluding means positioned and arranged to exclude wind and moisture when the sashes are between the outer grooves and in the vertical position.

It includes releasable fastening means permitting the sashes to remain in a vertical position while they are raised and lowered along the vertical grooves.

It includes clamping means for locking the lower sash in its closed position which effectually locks both of the sashes and prevents them from being opened from without.

It includes diagonal grooves connecting the lower ends of the vertical outer and inner guide grooves, permitting the lower sash to be transferred from a position between the outer grooves to positions between the inner grooves, and transverse grooves spaced above the inclined grooves in which pivot pins connecting the aforesaid links to sash cord clips can move to enable the said pivot pins and ends of the cords attached thereto to travel from the outer to the inner vertical grooves and vice versa.

It also includes arc shaped grooves extending inwardly and downwardly from the lower ends of said outer vertical grooves in which the pivot pins on which the sashes are mounted may move to permit the lower and upper sashes to be tilted to a horizontal position.

It includes connecting means between the latches at the sides of the sashes permitting them to be operated simultaneously to be disengaged from the adjacent links.

The invention further includes the combination and arrangement of parts and construction of the various details, hereinafter described, shown in the accompanying drawings, and specifically pointed out in the claims.

In the accompanying drawings, Fig. 1, is a perspective of the window frame showing

the lower sash pivots in the inner vertical grooves and the sash tilted forward and the upper sash in the raised position between the upper outer grooves; Fig. 2, is a vertical section showing both sashes in the same vertical plane and in a closed position between the outer grooves; Fig. 3, is a similar view showing the lower sash in the extreme lowered position and tilted so as to lie substantially horizontal with its pivots in the curved grooves, 20, 20, connected with the lower ends of the vertical grooves, 7 and 8; Fig. 4, is a similar section showing the lower sash tilted slightly forward and partially raised with its lower pivots in the inclined grooves and the upper sash partially lowered; Fig. 5, is a similar section showing the lower sash elevated with its lower pivots and link pivots in the inner grooves and partially swung inward and the pivots in the lower end of the upper sash lowered into the curved grooves at the bottom of the outer grooves the sash lying substantially horizontal and the holding link pivots guided in the outer groove. Fig. 6, illustrates the positions of the sashes when both sashes are slightly tilted forward to provide ventilating openings over their upper ends. Fig. 7, is a front elevation of an extremely wide sash showing connecting means between the side latches enabling them to be simultaneously operated. Figs. 8 and 9, are side and front elevations respectively of one the lower sash supporting links. Figs. 10 and 11, are similar views of the upper sash supporting link and its shoe which serves to prevent the link supporting the upper sash from entering the transverse groove connecting the vertical grooves. Fig. 12, is a transverse section through the upper sash and frame.

In these views, 1, is the window casing provided with the outer stop member, 24, on its bottom face.

4, is the upper sash and 5, the lower sash which when vertically positioned in the frame rest against the stop members.

The sides 6, 6, of the frame are provided with spaced outer and inner vertical grooves 7 and 8 respectively in which the pivot pins 9 and 10 adjacent to the lower ends of the upper and lower sashes are guided.

At its lower end the inner groove 8 is turned diagonally downward and outward at 11, to communicate with the lower end of the outer groove 7 and just below the top of the lower sash when in fully closed position the vertical grooves are connected by means of a horizontal groove 13, the purpose of which will be hereinafter pointed out.

The weight of the lower sash is supported by means of the cords, 60, 60, and counterbalance weights, 61, 61, attached to the upper ends of the link members, 14.

The link members are provided at their upper ends with guide pins, 16, that are movable in the grooves, 7 and 8, and at their lower ends the links are pivotally connected with the edges of the sash by guide pins, 18.

The weight of the upper sash is similarly supported by means of links, 15, 15, and similar cords and counterbalance weights.

The upper ends of the links, 15, are provided with pivoted shoes, 17, which travel in the outer vertical grooves, 7, but bridge the horizontal grooves, 13, and cannot enter them. The lower ends of the links, 15, are pivoted to the edges of the sashes at 19.

These links permit the window sashes to swing inwardly at their upper ends sufficiently to provide ventilating openings at their upper ends. Also, when lowered to the bottom of the casing, the upper ends of the sashes can be swung on their lower pivots, 9 or 10, to substantially the horizontal position shown in Figs. 3 and 5, independently of each other, so they will be accessible for cleaning.

This is permitted by providing downwardly and inwardly curved grooves, 20, in the sides of the casing communicating with the point of juncture of the inclines and vertical outer grooves, in which the lower pivot pins of the sashes travel, and which guide the lower pivots away from the outer grooves and permit the swinging of the sashes.

When closed for the night, the two sashes may be vertically disposed in the same plane between the outer grooves, 7, and have interlocking adjacent edges at 21, 21, which comprise shoulders formed at different levels, that effectually exclude the weather.

Also, at the lower end of the lower sash, a groove, 22, in the sash, is engaged by a ridge or head, 23, on the stop member, 24, which is secured to the sill, 25, for the same purpose.

At the upper end of the upper sash the weather stop, 26, prevents entrance of moisture. When it is desired to swing open the lower sash, the upper end thereof is swung inward as shown in Fig. 4, and the pivot pins, 16, at the upper ends of the links, 14, are made to transverse the horizontal grooves, 13, until they enter the inner vertical grooves, 8, in the casing or frame.

The sash is then lowered until the lower pivot pins enter the downwardly curved grooves, 20, 20, when the upper ends of the sash can be swung downward until the sash assumes the substantially horizontal position shown in Fig. 3 and is brought forward to release the ridge 23 on the stop member from the groove 22 in the lower bar of the sash. The downwardly and inwardly curved grooves or slots, 20, permit this action.

When the lower sash is tilted forward the upper sash can be lowered as shown in Fig. 4 and when the lower sash has been raised along the inner grooves by passing its lower 5 pivots through the inclined grooves connecting both grooves at the bottom, the upper sash can then be lowered further as shown in Fig. 5, until its lower pivots can then be passed into the curved grooves and 10 the upper end of the sash can be swung into a substantially horizontal position in the same manner as the lower sash to give it accessibility for cleaning on both sides.

Heavy latches 30, 30, on the lower sash 15 prevent both of the sashes from being moved from the outside by irresponsible people and spring actuated latches 31, 31, in the sides of the sashes engage the outer edges of the link members and prevent the sashes 20 from swinging inwardly at the top while they are being raised and lowered, until they are manually released.

In Fig. 7, a central rotatable knob 40, is employed which is operatively connected 25 with both of the latches 31 by means of cords 41, passing over pulleys 42, and spring actuated bell cranks 43.

The pivots 9 and the shoes 17 for the upper sash always move in the outer groove 30 and the links are sunk in recesses 80 in the sides of the sashes, to permit free movement thereof.

Vertical ribs 45, on the rear edges of the sashes enter corresponding grooves 46, in 35 the vertical stops upon the outer edges of the sides of the casing to make them weather proof.

Having described the invention what I claim as new and desire to secure by Letters Patent is:

1. In a window of the character described, the combination with the casing, said casing provided with parallel spaced outer and inner vertical grooves on its opposite sides, each inner groove being connected to the adjacent outer groove by means of an inclined groove at its lower end, of upper and lower sashes, said sashes being provided with pivot guides adjacent to their lower ends, and said guides movable in said grooves, and link members pivoted to the side bars of said sashes at their lower ends, and provided with guides at their upper ends, said upper guides movable in said grooves, and spring pressed latches adapted to engage the outer edges of said link members to prevent the said sashes from being tilted inwardly while being raised and lowered in said grooves.

2. The combination with a window casing, of upper and lower sashes movable therein, the opposite inner faces of said window casing being provided with horizontally spaced vertical guide grooves, pivot pins carried by said sashes adjacent to their

lower ends and movable in said guide grooves, said grooves on each side being connected adjacent to their lower ends by means of inclined slots, and by means of transverse slots, intermediate of their ends, links pivoted 70 at their lower ends to said sashes, pivots in the upper ends of said links, said pivot pins being movable in said vertical grooves, and counterbalance cords connected with said pivots, the pivot pins for the lower end of 75 the lower sash being movable in said inclined grooves into said inner vertical grooves, and the pivots at the upper ends of said links on the lower sash comprising pins movable through said transverse 80 grooves into said vertical inner grooves.

3. The combination with a window casing, of upper and lower sashes movable therein, the opposite inner faces of said window casing being provided with horizontally spaced vertical guide grooves, pivot pins carried by said sashes adjacent to their lower ends and movable in said guide grooves, said grooves on each side being connected adjacent to their lower ends by means of inclined slots, and by means of transverse slots, intermediate of their ends, links pivoted 90 at their lower ends to said sashes, pivots in the upper ends of said links, said pivot pins being movable in said vertical grooves, and counterbalance cords connected with said pivots, the pivot pins for the lower end of 95 the lower sash being movable in said inclined grooves into said inner vertical grooves, and the pivots at the upper ends of said links on the lower sash comprising pins movable through said transverse 100 grooves into said vertical inner grooves, the pivots at the upper ends of the links for the upper sash comprising shoes adapted to bridge over said transverse slots.

4. The combination with a window casing, of upper and lower sashes movable therein, the opposite inner faces of said window casing being provided with horizontally spaced vertical guide grooves, pivot pins carried by said sashes adjacent to their lower ends and movable in said guide grooves, said grooves on each side being connected adjacent to their lower ends by means of inclined slots, and by means of transverse slots, intermediate of their ends, links pivoted 110 at their lower ends to said sashes, pivots in the upper ends of said links, said pivot pins being movable in said vertical grooves, and counterbalance cords connected with said pivots, the pivot pins for the lower end of 115 the lower sash being movable in said inclined grooves into said inner vertical grooves, and the pivots at the upper ends of said links on the lower sash comprising pins movable through said transverse 120 grooves into said vertical inner grooves, the pivots at the upper ends of the links for the upper sash comprising shoes adapted to bridge 125 130

over said transverse slots, the sides of said casing being also provided with inwardly and downwardly extending grooves, communicating with the lower ends of said inclined and inner vertical grooves, in which said lower pivot pins in said sashes may fall and rotate.

In testimony whereof, we hereunto set our hands this 4th day of January, 1922.

MIKE SUSTARSIC.
LOUIS FLORJANCIC.
